Patented Aug. 22, 1916.

UNITED STATES PATENT OFFICE.

JULIUS H. G. WOLF, OF OAKLAND, CALIFORNIA.

CONCRETE RAILROAD CROSS-TIE.

1,195,634.

Specification of Letters Patent. Patented Aug. 22, 1916.

Application filed September 5, 1911, Serial No. 647,669. Renewed February 2, 1915. Serial No. 5,778.

To all whom it may concern:

Be it known that I, JULIUS H. G. WOLF, a citizen of the United States, residing at Oakland, in the county of Alameda and State of California, have invented new and useful Improvements in Concrete Railroad Cross-Ties, of which the following is a specification.

This invention relates to an improvement 10 in composite railway cross ties and the means for securing the rails thereon.

The expansion of the volume of railroad traffic, together with the greater train-weights and train-speeds upon modern rail-ways have set up conditions that are making 15 the road-beds as heretofore constructed inadequate for the heavier service. The present mode of construction thereof, having reference in particular to the wood cross ties 20 or sleepers, cannot meet the new conditions with economy.

As a material for making cross ties wood has ranked first with past conditions on the 25 grounds of suitability, adaptability, and first cost. Owing to the lessening supply of hard-wood timber, and the fact that the heavier train-weights destroy the fibers of the wood even though decay is resisted by expensive treatment processes, the first, as 30 well as the ultimate, cost of the wood tie is growing prohibitive.

In this invention the purpose is to make a tie which shall have the form, the qualities, and the adaptability to service, of the wood 35 tie, yet shall possess greater resistant properties, be cheaper in maintenance and ultimate cost, and be of such nature and of such design that its strength and form can be varied to meet the demands of any future 40 railway traffic as heavier requirements are developed.

Particular objects of the invention are to produce a tie, (1) with which, by using a richer mixture for the concrete, and the interposition of wire netting at, or near, the outer and inner concrete surfaces, there is obtained the protection necessary to resist disintegration, the common cause to date of failures of composite ties; (2) which, by the 45 use of vertical-shear members in the reinforcing elements fulfills the conditions necessary to prevent center-cracking and disruption when the tie becomes center-bound; (3) which, by the use of a suitable attachment 50 device and cushioning that prevents the strains from the imposed train-weights coming in contact with the tie body, insures

against disintegration of the concrete from this cause, the most common cause of concrete tie failures; (4) which, being of hollow form and having the concrete raised under the rail and provided with a shoulder therein, resists the train-thrusts on curves, and positively prevents spreading of the rails, the cause of many railroad wrecks; (5) 60 which, from its hollow form, will pass flood-waters through the track during periods when high waters impinge against the railroad embankment and threaten to wash it out; (6) which, from its form and weight, 65 can be handled and tamped like any ordinary wood-tie, and can without radical track-reconstruction work be individually inserted in tracks already constructed as the wood ties require renewal. These are features 70 of the greatest practical importance.

Having thus described the objects of the invention, a practical embodiment thereof is represented in the accompanying drawing, forming part of this specification, in which 80 similar characters of reference indicate corresponding parts in all the views.

Figure 1 is a top plan view of the tie; Fig. 2 is an enlarged longitudinal vertical section of one end thereof; and Fig. 3 is a 85 cross-section on the line 3—3 of Fig. 2.

In carrying out this invention there is employed a hollow body 1 of concrete, in which is embedded a longitudinal reinforcement 90 2 consisting of wire cloth or of expanded metal formed cross-sectionally in the shape of a closed polygon, and extending the length of the tie, and bars 3, which may be of any form, such as twisted steel, or deformed bars used ordinarily to obtain 95 transverse strength in reinforced concrete construction. The wire cloth or expanded metal and the bars constitute the primary reinforcement for transverse strength; the wire cloth or expanded metal have the additional function of being likewise a reinforcement against the disruption of the concrete. The concrete should preferably be made fairly rich in cement, and should be dense in texture, to effect which result hydrated 105 lime to the extent of 10% of the cement used, may be added in proportioning the ingredients. To furnish other protection for vertical shear in addition to that provided by the vertical members of the wire cloth, 110 vertical wire-inserts 18 may be added between the vertical members of the wire cloth. To provide against initial checking or cracking of the concrete from the train-

rattle, and the disintegration of the body resulting therefrom, there is embedded near the outer surface of the concrete a sheet of wire netting 5, which may be in the form of light diagonal netting, or the so-called "chicken netting." This netting is likewise in the shape sectionally of a closed polygon so as to constitute an envelop. Where the demands of traffic are particularly heavy and a tie of extra-resistant quality is demanded, another envelop 6 of wire netting is embedded within the concrete mass near the inner surface. These netting envelops are not only resistant to incipient disintegration but also factors in affording the transverse strength of the tie.

The means for attachment of the rails is best shown in Fig. 2. The rail 7 is held to the tie by means of screw-spikes 8 which pass through a wooden tie plate 9. A steel tie-plate 10 may or may not be used in conjunction with the wooden tie-plate 9, but its use is preferable where heavy traffic prevails. Each screw-spike passes through a hole 11 in the upper side of the concrete body, so as to be free from contact with said body, and into an anchoring device, which is here shown as a block 12, preferably of wood, which is inserted endwise within the hollow body of the tie. The rectangular hole 11 is of such dimensions as to permit lateral adjustment of the attaching device on curves to accommodate the wider rail-gage at such points; this adjustment also accommodates the rail-joint ties, making one uniformly cast tie serve either as a rail-joint tie or as an intermediate tie.

Through the interposition of a cushion 13 of felt, sheet-rubber, or other yielding substance, between the block 12 and the concrete body 1, and a like cushion 14 between the tie-plate 9 and said body 1, the shock from passing train-weights is absorbed and is prevented from reaching said body 1. With trains on curves, the train-thrust is transmitted through the tie-plate 9 to shoulders 15 formed in the concrete body. In practice the height of the shoulder 15 may be as great as the depth of the wood cushion plate 9, and the slopes of the shoulder, instead of curving sharply, can taper gradually to the outer end of the tie in the outward direction, and to the middle of the tie in the inward direction. These shoulders also resist the tendency of the rails to spread. The function of the block 12 is also to distribute the strains, incident to holding the rail to the tie, over an area of 50 to 75 square inches instead of upon a few square inches as in rigid attaching devices. By this mode of attachment the concrete is subjected to no strains whatsoever excepting through the medium of substances of compressible fibers in conjunction with specially provided cushions. The necessity for

this elimination of strains, as a provision against the masonry's disruption, has in current practice for some years past been demonstrated to be necessary in all lines of reinforced concrete construction.

The term "open metallic reinforcing material" as used in the claims herewith is defined to mean any metallic material used in the art of reinforced concrete construction, such as for example the wire cloth of commerce (exemplified by the Clinton electrically welded wire cloth), or expanded metal, or the expanded wire-lath of commerce, materials which possess like functions and like qualities, and, although differing slightly in structure, perform the same service. Where the expanded metal or the wire-lath is used, the vertical shear wire-inserts 18 may be fastened in position by wiring to the bars 3.

The word "concrete" is defined as meaning any composite material which has as its basis the Portland cement of commerce, or a similar cementing substance, combined with an aggregate of sand and broken stone, or any like materials or substances used in a similar way in the aggregate.

The drawings and the description of the invention as herewith disclosed have reference particularly to its application to steam railway service. I do not limit its application to this service alone, but claim its adaptability, with possibly slight modifications of the manner of attaching the rail to the tie, to the tracks of urban and interurban electric and street car service as well.

The design herewith disclosed allows of a construction in which the rail-attaching device is free from contact with, and independent of, the tie structure, thereby keeping the disrupting stresses produced by the train rattle and impact blows from affecting the concrete mass of the tie. This freedom from direct contact with the interior steel construction likewise reduces the electrolytic action which may be induced between the exterior or superimposed steel elements and the interior reinforcing steel. This condition, which is most important for a successful composite tie, has not heretofore been obtained in composite tie construction.

While the above constitutes what is considered the preferred form of this invention, slight modifications, variations and alterations of structural details may be resorted to without violating the principles involved therein, and the right is reserved to make slight changes within the scope of the invention as practice may show to be desirable.

I am aware that it has been proposed to form a hollow concrete body with a plurality of envelops of wire netting embedded therein, but such wire netting was used for reinforcing only, or as a skeleton for carrying plastering. Applicant's wire netting is

placed close to the surface. By the words "closely adjacent" in the claim, applicant defines the distance of the wire envelop from the adjacent surface as being much less than, 5 at least one half as small as, that between the two envelops. This netting in this particular position in the concrete body is to prevent the initial cracking or checking of the concrete, leading ultimately to the disintegration of the concrete body. On the other hand applicant's principal reinforcing member consists of wire-cloth (as for instance, the Clinton electric welded wire-cloth) or any open metallic reinforcement 10 placed in a median zone of the concrete body, and in the angles thereof are located longitudinal bars particularly adapted to take the bending strains. These rods are an essential part of the tie structure and ex- 15 tend the length of the tie. The wire-cloth is likewise a very essential part of the tie structure in taking care of the vertical shear strains when the tie is loaded as a beam. The wire-cloth and the reinforcing rods are 20 independent in both function and structure from the wire netting in, or contiguous to, the concrete surfaces.

I claim:

1. A railway cross tie comprising a hollow body of concrete, having polygonal outer and inner surfaces, polygonal envelops of wire netting embedded in said concrete closely adjacent respectively to said surfaces, a longitudinal open metallic reinforcement between said polygonal envelops, formed cross sectionally in the shape of a closed polygon and extending the length of the tie, and longitudinal bars embedded in the concrete within and closely adjacent respectively to the inner angles of the open metallic reinforcement, and each extending substantially the length of the tie.

2. A railway cross tie consisting of a tubular integral body of concrete having an upper inner surface of substantially uniform height the entire length of the tie, and an upper outer surface which is raised in the parts that are beneath the rail, an envelop of wire netting embedded in the concrete closely adjacent to the upper surface of the tie, both in the main depressed portion and in its elevated part beneath the rail, an envelop of wire netting embedded in the concrete closely adjacent to the inner surface, a polygonal shell of open metallic reinforcement embedded longitudinally in said concrete, and longitudinal bars extending substantially the length of the tie and embedded in the concrete within, and adjacent to, the angles of the shell.

3. A railway tie consisting of a tubular integral body of concrete having an upper inner surface of substantially uniform

height the entire length of the tie, and an upper outer surface which is raised in the parts that are beneath the rails, said tie being formed on its upper surface with shoulders to receive the thrust of the rail, and an envelop of wire netting embedded in the concrete closely adjacent to the upper surface of the tie both in its main depressed portion and in its elevated parts beneath the rails, and following the contour of the upper surfaces of the shoulders.

4. A railway cross tie consisting of a tubular integral body of concrete having an upper inner surface of substantially uniform height the entire length of the tie and an upper outer surface which is raised in the parts that are beneath the rail, said tie being formed on its upper surface with shoulders to receive the thrust of the rail, and an envelop of wire netting embedded in the concrete closely adjacent to the upper surface of the tie both at its main and depressed portion and in its elevated parts beneath the rail, and following the contour of the upper surfaces of the shoulders, an envelop of wire netting embedded in the concrete closely adjacent to the inner surface of the tie, a polygonal shell of open metallic reinforcement embedded longitudinally in said concrete, and longitudinal bars extending substantially the length of the tie and embedded in the concrete within, and adjacent to, the angles of the shells.

5. A railway cross tie consisting of a tubular integral body of concrete and longitudinal metallic reinforcement and wire netting embedded therein, the upper outer surface of the concrete adjacent to the rail-seat being raised to form a shoulder, the concrete having openings therethrough under the railseat to pass an attaching device for holding the rail to the tie independently of the tie structure.

6. A railway cross tie consisting of a tubular integral body of concrete and longitudinal metallic reinforcement and wire netting embedded therein, the upper outer surface of the concrete adjoining the rail-seat being raised to form a shoulder, an anchoring device within the hollow body and adapted to be passed through an open end thereof, the hollow body of the tie having openings above said device, and means secured to said device for holding the rail upon the tie.

In testimony whereof I have hereunto set my hand in the presence of two subscribing witnesses.
